(57) **CLAIM**

The ornamental design for a tackling training device, as shown and described.

DESCRIPTION

FIG. 1 is an upper isometric view of my new ornamental design for a tackling training device in accordance with the present disclosure;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof; and,

FIG. 7 is a bottom view thereof.

The broken lines illustrate portions of the tackling training device and form no part of the claimed design.
